UNITED STATES PATENT OFFICE.

ELBRIDGE T. LIKES, OF DES MOINES, IOWA.

BUILDING-BLOCKS.

1,124,478.

Specification of Letters Patent. Patented Jan. 12, 1915.

Application filed September 12, 1913. Serial No. 789,465.

To all whom it may concern:

Be it known that I, ELBRIDGE T. LIKES, a citizen of the United States, residing at Des Moines, in the county of Polk and State of Iowa, have invented new and useful Improvements in Building-Blocks, of which the following is a specification.

The present invention comprehends improvements in building blocks and relates 10 more particularly to means for reinforcing and connecting the blocks together.

It is the primary object of the present invention to provide a reinforcing for building blocks which will also be used for connecting and binding the blocks together to 15 form a rigid building wall.

Another object of the present invention is to provide a reinforcing of the character described, which will be comparatively inexpensive in the cost of manufacture, strong 20 durable and reliable when in use and having means whereby the building blocks may be readily and easily tied together.

With the above and other objects in view, 25 this invention consists of the novel features of construction, the combination, formation and arrangement of parts, as will be herein-after more fully described and as particularly pointed out in the claim.

30 In the accompanying drawings has been illustrated the simple and preferred forms of my invention, it being understood that no limitation is necessarily made to the precise structural details therein exhibited, but the 35 right is reserved to make any changes to which recourse may be made within the scope of the invention, without departing from the spirit thereof.

In the drawings: Figure 1 is a front elevation of a pair of building blocks embodying my invention. Fig. 2 is a horizontal section of the same taken on the line 2—2 of Fig. 1. Fig. 3 is a vertical sectional perspective view of one of the building blocks, 45 and Fig. 4 is a vertical transverse section taken on the line 4—4 Fig. 1.

The building blocks A and B as shown in the accompanying drawing consist of the ordinary material and are made rectangular 50 in formation to illustrate the present invention, but it is of course understood that these building blocks may be of any configuration, suitable for any building purposes. Each of the said building blocks have centrally 55 located therein a net work C forming a suitable reinforcement to insure durability to

the blocks, which consist preferably of strands of wire having the opposite ends thereof protruding beyond the sides of the block, which when connected with the protruding ends of the adjacent block will form a binding tie. To provide means for tying and reinforcing the upper and lower ends of the blocks, I provide a connection D comprising longitudinally extending rods which 60 rest within recesses upon the upper and lower faces of the blocks. 65

In more specifically describing the present invention, the net work C comprises a plurality of longitudinally extending strands 70 of wire 1, which are suitably spaced apart within the central portion of each block between the upper and lower edges thereof. These horizontal wires 1 are connected by vertical strands of the wire 2 which are embedded within the block and having their opposite ends terminating adjacent the upper and lower edges of each block. These vertical and horizontal wires 1 and 2 cross each other first above and then under, to 75 form a connection which will prevent the strands from pulling apart when embedded within the building blocks. As more clearly shown in Figs. 1 and 3 of the drawing, the upper, lower and central horizontal strands 80 1 protrude beyond the opposite ends of the blocks to provide means whereby the said ends may be tied to similar protruding ends of the adjacent blocks. 85

In building a wall, one of the blocks A is 90 first placed in position and a block B is positioned adjacent thereto. The protruding ends 3 of the wires are then twisted together, as indicated by the numeral 4 in Figs. 1 and 2 of the drawing, thereby forming a 95 binding tie between the ends of the blocks. The block B is then forced against the block A but leaving a space 5 between the adjacent ends, in which is placed mortar for concealing the same. From the foregoing, it is 100 obvious that the net work C will provide a suitable reinforcement for each building block, which when connected together will form a binding tie and when the mortar is placed within the opening 5, the blocks will 105 act as one continuous wall.

The connection D between the upper and lower ends of the blocks comprise longitudinally extending recesses 6 formed within the medial portion of the upper and lower faces 110 of the blocks, which I have shown substantially semi-circular in cross section. Within

these recesses are adapted to rest, the cylindrical rods 7 so that when the blocks are placed upon each other and mortared in, the rods 7 will also act as a binding tie as well 5 as a reinforcing member.

Whereas, in the accompanying drawings, I have illustrated the rod 7 as being cylindrical, it is of course understood that these rods may be rectangular or any other shape 10 or size desired and that the recesses should conform to the outer configuration of the said rods. These rods may also extend longitudinally across the entire building wall or they may be made in sections of the desired length. 15

I claim:—

A building wall comprising a plurality of blocks constructed of plastic material, the adjacent ends of the blocks being spaced 20 from each other, reinforcing means embedded in each of the blocks and embodying flexible elements projecting beyond the ends of the blocks, said elements being spaced from the lateral faces and also from the top 25 and bottom edges of the blocks, the elements of one block being twisted with the respective elements of the next adjacent block,

said twisted portion being arranged in the space between the ends of the blocks and spaced from the lateral faces of the blocks, 30 said blocks each having open grooves in their top and bottom edges in substantial alinement with the reinforcing material, but spaced therefrom, said grooves having open ends, the grooves of adjacent blocks coöperating to form substantially continuous seats, and additional reinforcing elements seated in the grooves and extending across the space between adjacent edges of the blocks, the said space being filled with a 40 bonding material, the twisted portions of the first recited reinforcing elements, and the portion of the said additional reinforcing elements which extend across the spaces between the blocks being embedded in the 45 said bonding material.

In witness whereof, I hereunto subscribe my name to this specification in the presence of two witnesses.

ELBRIDGE T. LIKES.
